(57) CLAIM

The ornamental design for an instrument for visceral manipulation as shown and described.

DESCRIPTION

FIG. 1 is a top, front, right-side perspective view of an instrument for visceral manipulation according to the present invention;

FIG. 2 is a bottom, front, left-side perspective view thereof;

FIG. 3 is a front elevation view thereof;

FIG. 4 is a rear elevation view thereof;

FIG. 5 is a right-side elevation view thereof, where the left-side elevation view is a mirror image thereof;

FIG. 6 is a top plan view thereof; and,

FIG. 7 is a bottom plan view thereof.
